DOOR ARRANGEMENT

John L. Hearn, Upper Darby, Pa.

Application March 14, 1935, Serial No. 11,019

5 Claims.

(Cl. 20—16)

This invention relates generally to swinging doors and more particularly to doors for locomotive equipment.

In certain types of locomotive equipment, especially those that are streamlined, it is necessary to place a swinging door in a slanting wall. While such a wall may be located in various parts of the locomotive cab, yet it is more commonly used in the front portion of the hood or cab which is inclined to give a streamlined effect. Under such conditions, the lower edge of an ordinary hinged or swinging door would strike the floor of the cab due to the inclined axis about which the door would swing and thus prevent complete opening of the door.

It is one object of my invention to provide an improved door construction whereby the door may be suitably hinged about its inclined axis and yet will permit complete opening. A further object is to provide an improved combination whereby the door will be automatically adjusted during its opening movement so that the same is not obstructed in any way notwithstanding that the door is so hung that it would under normal conditions strike the floor and prevent opening.

Another object is to provide improved means for holding the door after it is swung to its full open position, and to accomplish this by cooperation with the automatically adjustable features of the construction.

Other objects and advantages will be more apparent to those skilled in the art from the following description of the accompanying drawing in which:

Fig. 1 is a diagrammatic side elevation of the front end of a locomotive cab;

Fig. 2 is a horizontal sectional view taken on the line 2—2 of Fig. 1 but showing the door in its full closed position as contrasted to the full open position in Fig. 1;

Fig. 3 is an enlarged perspective view of one of the hinges employed in my improved combination.

In the particular embodiment of the invention which I have shown herein merely for the purpose of illustrating one specific form among possible others that the invention might take in practice, I have shown the invention as applied specifically to the front end of a locomotive cab generally indicated at 1, although it will of course be understood that the invention has other applications in which it is desired to place a swinging door in a slanting wall such as generally indicated at 2. The floor of the cab or other struc-

ture is generally indicated at 3. The door opening is provided with any suitable vertical posts 4 specifically shown as made of structural Z-shapes. A door sill 5 having a straight horizontal top surface or edge may be provided at the bottom of the doorway.

A door 6 is preferably supported at its upper and lower ends by a hinge construction generally indicated at 7. As shown in Fig. 3, each hinge comprises a fixed guiding stem 8 secured to bosses 9, these bosses being provided with studs 10 adapted as shown in Fig. 2 to pass through one leg of one of the Z-posts and secured thereto by nuts or riveted if desired. The door is secured to an angle member 11 supported preferably by screws 12 to one edge of the door. A guiding boss 13 is formed preferably integral with angle 11 and is adapted to slide on hinge pin 8.

Provision of the foregoing type of hinge at both the upper and lower ends of the door will permit the door to swing about an inclined axis while at the same time raising or lowering during the swinging movement as may be determined in accordance with the engagement of a roller 14 on a suitable arcuate track 15. This track is preferably secured to the floor or if desired it may be formed as part of the floor itself, but in any event it is preferable to provide a recess 16 to receive the roller when the door is in its fully open position. The roller itself is supported in any suitable manner on the door, although as specifically shown herein the roller is preferably supported in a U-shaped bracket 17 having flanges screwed to the door.

In operation, when the door is in its closed position, the guides 13 which are secured to the door will be adjacent the lowermost bosses 9. However, as the door swings open, the outer lower corner thereof will move downwardly toward the floor in which case roller 14 engages track 15, whereupon further opening movement of the door will cause the same to be moved upwardly along the axis of the hinge pins 8. In this manner, the adjustable elevation of the door compensates for the variable angularity between the bottom of the door and the floor 3 during opening movement of the door. Conversely as the door is closed, the weight thereof will cause the guides 13 to slide downwardly on hinge pins 8, thereby insuring that the bottom of the door 13 will be brought into substantial parallelism with the door sill 5 when the door is finally closed. When the door is in its full open position as shown in full lines in Fig. 1, or as shown in dotted lines at 18 in Fig. 2, the roller 14 will fall into recess 16 and be held

therein due to the weight of the door. As the roller drops into recess 16, the door will bodily drop to an extent equal to the depth of the recess, thereby providing a substantial holding force 5 against accidental reclosure of the door.

It will of course be understood that various changes in details of construction and arrangement of parts may be made by those skilled in the art without departing from the spirit of the 10 invention as set forth in the appended claims.

I claim:

- 15 1. A door construction comprising, in combination, an inclined wall having a doorway therein, a door therefor, pivotal supporting means forming an extended axis inclined the same as said wall and constituting the sole axis about which the door swings, and means for effecting vertical bodily movement of said door solely along said extended axis during swinging of the door.
- 20 2. A door construction comprising, in combination, an inclined wall having a doorway therein, a door therefor, a hinge adapted to support said door upon an axis inclined the same as said wall and including a guiding element and a hinge pin element extending therethrough, means for normally immovably securing one of said elements to said wall, means for normally immovably securing the other of said elements to said door whereby the door is adapted to be swung 25 around and maintain a uniform lateral relation to the axis of said pin throughout all door movement and bodily move vertically solely along the axis of said elements during swinging movement of the door, and means for effecting said bodily 30 movement.

axial movement of the door during swinging thereof.

3. A door construction comprising, in combination, an inclined wall having a doorway therein, a door therefor, means for pivotally and vertically movably supporting said door about an axis inclined the same as said wall and for maintaining a uniform lateral relation between said axis and door throughout all movement thereof, and means for effecting vertical bodily movement 10 of the door during swinging thereof.

4. A door construction comprising, in combination, an inclined wall having a doorway therein, a door therefor, means for pivotally and vertically movably supporting said door about an axis inclined the same as said wall and for maintaining a uniform lateral relation between said axis and door throughout all movement thereof, means for effecting vertical bodily movement of the door during swinging thereof, and means for 15 holding said door in its open position.

5. A door construction comprising, in combination, an inclined wall having a doorway therein, a door therefor, means for pivotally and vertically movably supporting said door about an axis inclined the same as said wall and for maintaining a uniform lateral relation between said axis and door throughout all movement thereof, means for effecting vertical bodily movement of the door during swinging thereof, means providing a floor recess, and a member carried by the 25 door for cooperation therewith to hold the door in open position.

JOHN L. HEARN.
